J. ROMEYN

TWO-STROKE INTERNAL COMBUSTION ENGINE

Filed July 3, 1923

FIG. 1

FIG. 2

FIG. 3

Inventor:

Jean Romeyn
By *Pauline Romeyn*
Attorney

UNITED STATES PATENT OFFICE.

JEAN ROMEYN, OF BRUSSELS, BELGIUM.

TWO-STROKE INTERNAL-COMBUSTION ENGINE.

Application filed July 3, 1923. Serial No. 649,349.

To all whom it may concern:

Be it known that I, JEAN ROMEYN, a citizen of the Kingdom of Netherlands, and resident of Brussels, Belgium, have invented certain new and useful Improvements in or Relating to Two-Stroke Internal-Combustion Engines; and I do hereby declare the following to be a full, clear, and exact description of the invention, such as will enable others skilled in the art to which it appertains to make and use the same, reference being had to the accompanying drawings, and to letters or figures of reference marked therein, which form the part of this specification.

In a two-stroke internal combustion engine, as is well known, the maximum output which can be obtained from a given cylinder depends upon the back pressure in the exhaust pipe.

Two different cases of an increase in the back pressure will now be discussed, supposing all the other conditions to be unaltered.

Firstly, if the engine is so designed that the scavenging valves or parts close after the exhaust ports have closed again the back pressure increase results in the pressure in the cylinder during the scavenging period becoming higher, and the same applies to the scavenging air pressure. Consequently, as the cylinder is filled at a pressure substantially equal to the scavenging air pressure, the pressure at the beginning of the compression is higher, and more fresh air is compressed by the piston.

Secondly, if the scavenging is effected through ports only, and without any additional distributing arrangement, these ports, which necessarily open after the exhaust ports, are closed first and the pressure at the beginning of the compression is substantially equal to the back pressure in the exhaust pipe. In this case it is obvious that any increase of this back pressure is favourable as regards the quantity of fresh air enclosed in the cylinder.

It would be very easy to obtain any given back pressure in the exhaust pipe by arranging at the end thereof a restricted passage if the lead and the speed of the engine were constant. But, as the volume of burnt gas exhausted by the engine in a time unit is

variable owing to the exhaust temperature, and as the case may be, to the speed of the engine, the back pressure obtained by means of a restricted passage of constant area would vary and consequently also the compression pressure. Such variations of the compression are only permissible when they are slight.

Therefore it has been proposed to put in the exhaust pipe a valve, the opening of which can be adjusted by hand or automatically according to the load and speed of the engine. But such a valve is liable to become clogged owing to the dirt of the exhaust gas.

The object of the present invention is to obtain a certain regulation of the back pressure without using any valve or mechanism in the exhaust pipe; and to effect this, there is discharged into the exhaust pipe a variable quantity of scavenging air, in such a manner that the flow of fresh air meeting with the flow of burnt gas creates disturbance and so increases the resistance encountered by said gas.

In order that the invention may be readily understood, it is represented by way of example in the accompanying drawings in which: Figure 1 is a diagrammatic vertical section, showing the invention in its simplest form; Fig. 2 is a similar sectional view of a form analogous to that illustrated in Fig. 1, but equipped with an obstructing element; and Fig. 3 is likewise a diagrammatic, vertical sectional view, but showing the invention applied to the exhaust silencer.

In Figure 1 the burnt gas flows through the pipe *b* *c* in the direction shown by the arrow *a*; *d* is an annular space or chamber encircling pipe *c* and receiving through the pipe *e* a certain quantity of scavenging air which can be adjusted by means of the valve *f*, which as the case may be is controlled by hand, or by the governor or by the speed regulating gear. The chamber *d* communicates with the pipe *c* through an annular slot *g*, which is so disposed that the flow of fresh air entering the pipe is directed backwards with respect to the direction of the burnt gas flow.

It must be considered that for a given

load and speed of the engine, the total volume of fluid (air and exhaust) which must pass through the mouth h of pipe e is constant. If the valve f is closed, the whole quantity of gas flows gently in the direction a without encountering other resistances than those caused by the pipe. But if part of the scavenging air is admitted through the slot g , there is an additional resistance 10 due to disturbance.

Supposing that the area of the pipe is suitable for obtaining at full load and full speed the back pressure and the compression required, it will be possible to suppress or 15 to minimize the differences of compression due to the variations of load and speed by admitting more or less fresh air through the pipe e .

In Figures 2 and 3, the same letters designate similar parts as in Figure 1. The form shown in Figure 2 is similar to that shown in Figure 1, except that the part i is inserted in the pipe e at the place where the scavenging air is admitted, in order to have an 25 annular passage h of small width, which is favourable to the disturbance.

In Figure 3 the device is applied to the exhaust silencer J but the principle is just the same.

30 What I claim is:

1. An attachment for two-stroke internal combustion engines, for regulating the back pressure within the engine cylinder in accordance with the load and speed of the engine, said attachment comprising: a hollow element to receive the exhaust gases from the engine, a discharge pipe for said gases opening into the receiving element, and means for admitting a supply of fresh 40 air into said element to impact against the exhaust gas current and thereby create a disturbance therein which will resist the passage of said current.

2. An attachment for two-stroke internal combustion engines, for regulating the back pressure within the engine cylinder in accordance with the load and speed of the engine, said attachment comprising: a hollow element to receive the exhaust gases 50 from the engine, a discharge pipe for said gases projecting at its inlet end into the receiving element, said element providing an internal chamber which encircles the projecting end of said pipe and which communicates with the bore of the latter through an annular slot, and a pipe for supplying fresh air to said chamber to pass into the discharge pipe by way of said slot and to impact against the exhaust gas.

60 3. An attachment for two-stroke internal combustion engines, for regulating the back pressure within the engine cylinder in accordance with the load and speed of the engine, said attachment comprising: a hollow element to receive the exhaust gases

from the engine, a discharge pipe for said gases projecting at its inlet end into the receiving element, said element providing an internal chamber which encircles the projecting end of said pipe and which communicates with the bore of the latter through an annular slot, and a pipe for supplying fresh air to said chamber to pass into the discharge pipe by way of the slot and to impact against the exhaust gas; said slot being so disposed that the current of incoming air flows therethrough in a direction substantially opposite that of the gas current. 70 75

4. An attachment for two-stroke internal combustion engines, for regulating the back pressure within the engine cylinder in accordance with the load and speed of the engine, said attachment comprising: a hollow element to receive the exhaust gases 80 from the engine, a discharge pipe for said gases projecting at its inlet end into the receiving element, said element providing an internal chamber which encircles the projecting end of said pipe and which communicates with the bore of the latter through an annular slot, and a pipe for supplying a certain quantity of scavenging air to said chamber to pass into the discharge pipe by way of said slot and to impact against the exhaust gas. 85 90 95

5. An attachment for two-stroke internal combustion engines, for regulating the back pressure within the engine cylinder in accordance with the load and speed of the engine, said attachment comprising: a hollow element to receive the exhaust gases from the engine, a discharge pipe for said gases projecting at its inlet end into the receiving element, said element providing an internal chamber which encircles the projecting end of said pipe and which communicates with the bore of the latter through an annular slot, a pipe for supplying fresh air to said chamber to pass into the discharge pipe by way of said slot and to impact against the exhaust gas, and a throttling device in the air supply pipe for controlling the flow of air therethrough. 100 105 110

6. An attachment for two-stroke internal combustion engines, for regulating the back pressure within the engine cylinder in accordance with the load and speed of the engine, said attachment comprising: a hollow element to receive the exhaust gases from the engine, a discharge pipe for said gases projecting at its inlet end into the receiving element, said element providing an internal chamber which encircles the projecting end of said pipe and which communicates with the bore of the latter through an annular slot, a pipe for supplying fresh air to said chamber to pass into the discharge pipe by way of said slot and to impact against the exhaust gas, and an 115 120 125 130

obstructing element mounted in the inlet end of said discharge pipe to provide an annular inlet space between the walls of the latter and of the obstructing element, there-
5 by to increase the disturbance initially created in the receiving element by the impact of the air and gas.

In testimony whereof I affix my signature in the presence of two witnesses.

JEAN ROMEYN.
